UNITED STATES PATENT OFFICE.

GEORGE E. ROBINSON, OF EUGENE, OREGON.

ADJUSTABLE BOW- SOCKET AND REST-CLAMP.

1,156,494.

Specification of Letters Patent.

Patented Oct. 12, 1915.

Application filed July 28, 1914. Serial No. 853,743.

To all whom it may concern:

Be it known that I, GEORGE E. ROBINSON, a citizen of the United States, residing at Eugene, in the county of Lane and State of Oregon, have invented certain new and useful Improvements in Adjustable Bow-Sockets and Rest-Clamps, of which the following is a specification, reference being had therein to the accompanying drawing.

10 This invention relates to adjustable bow sockets and rest clamps, and has for its object the production of a simple and efficient means for holding the bows adapted to support the top of an automobile or other vehicle in an assembled position when folded.

Another object of the invention is the production of a simple and efficient connecting device for holding the bows in an assembled position when the top is folded, and 20 which means may be normally carried by one of the bows so as to be normally out of the way and at all times be in a position for operation.

With these and other objects in view this 25 invention consists of certain novel combinations, constructions, and arrangement of parts as will be hereinafter fully described and claimed.

In the accompanying drawings Figure 1 30 is a side elevation of the device applied to an automobile. Fig. 2 is a side elevation showing the device holding the bows in an assembled folded position. Fig. 3 is a vertical section through the clamp showing the 35 bows held in an assembled position. Fig. 4 is a detail perspective of the adjustable clamping bar for holding the bows in an assembled position. Fig. 5 is a detail perspective of the lower adjustable link adapt- 40 ed to coöperate with the primary link. Fig. 6 is a detail perspective of the bow rest showing the manner in which the retaining bar engages the same. Fig. 7 is a side elevation partly in section showing the manner 45 in which the retaining bar engages the suspending bolt. Fig. 8 is a section taken on line 8—8, of Fig. 3 showing the thumb screw in elevation. Fig. 9 is a vertical section taken through a pair of bows showing 50 the interlocking sockets carried thereby.

By referring to the drawings it will be seen that 1 designates the vehicle such as an

automobile or other suitable vehicle which carries a suspending bolt 2 upon each rear side as is usual, which bolt 2 is suspended 55 from a bracket 3 carried by the body of a vehicle. The bolt 2 is provided with a laterally extending end 4, which laterally extending end 4 is provided with a notch 5 at one end for the purpose of firmly engaging 60 the flat face 6 of the lower adjustable link 7 as clearly illustrated in Fig. 7. The link 7 is provided with an enlarged aperture 8 for fitting over the laterally extending end 4 of the bolt 2 as is illustrated in Figs. 3 and 7. 65 The link 7 is provided with an elongated slot 9 for the purpose of allowing the same to be vertically adjusted relative to the primary link 10. The primary link 10 is provided with an upwardly rolled lower end 11 70 comprising a pair of spaced ears 12, which are adapted to engage or fit into the elongated slot 13 carried by the socket 14 to be hereinafter described. A thumb screw 15 passes through the longitudinally extending 75 slot 9 of the link 7 and is threaded into the primary link 10 for firmly locking the adjustable link 7 in a set position relative to the primary link 10.

The primary link 10 is carried by the 80 forward bow 16 of the top of the automobile, and this primary link is provided with a longitudinally extending slot 17, which longitudinally extending slot 17 is adapted to receive the threaded bolt 18 carried by 85 the top bow 16 clearly illustrated in Fig. 3. A plurality of notches 19 are formed along the respective side edges of the primary link 10 as illustrated in Fig. 4, and this primary link 10 is formed concavo-convex in cross- 90 section as illustrated in Fig. 8.

A retaining plate 20 is carried by the forward bow 16 and this retaining plate comprises an elongated body having a longitudinally extending rib 21 arranged upon 95 either side of the threaded bolt 18 above described. This rib 21 is preferably formed V-shaped in cross-section for the purpose of fitting in the notches 19 formed along the respective side edges of the primary link 10, 100 and thereby holding the link in an adjusted position.

When the cover of the automobile is in a set up position as illustrated in Fig. 1, the

primary link 10 is swung so as to extend parallel with the forward bow as illustrated in Fig. 1, and the auxiliary or adjustable link 7 is detached from the laterally extending portion 4 of the bolt 2 and carried by the primary link 10. Owing to the fact that the primary link 10 as well as the adjustable or auxiliary link 7 is concavo-convex in cross-section, the same will readily conform to the contour of the bow and in this way lie flat against the forward end of the bow 16 when the cover is in a set up position.

Each of the bows which support the top of the automobile is provided with the usual 15 interlocking sockets 22 for the purpose of causing the bows to remain in their correct alignment while the cover is being folded to the position shown in Fig. 2.

When the cover is folded to the position 20 shown in Fig. 2, the primary link 10 is swung at substantially right angles to the forward bow 16 as illustrated in Fig. 2, and the aperture 8 of the adjustable link 7 is slipped over the laterally extending end 4 25 of the bolt 2 so as to cause the straight edge 6 of the aperture to fit snugly within the pocket 5 of the laterally extending end 4, whereupon the thumb screw 15 is tightened for holding the adjustable link 7 in a set 30 position relative to the primary link 10. The upwardly rolled end 11, however, is first fitted into the aperture 13 of the socket 14 and thereby firmly holds the several bows in a firm position or locked assembled position while the same are in a folded position. 35 It should be understood that the rear bow 23 is adapted to rest in the concavo-convex face of the socket 14, and this socket 14 is provided with a collar 24 adapted to fit over 40 the laterally extending end 4 of the bolt 2, and this collar 24 is firmly held upon the laterally extending end 4 by means of the adjustable bolt 25.

From the foregoing description it will be 45 seen that a very simple and efficient device has been produced for the purpose of holding the cover of an automobile in a closed or folded position, and that the mechanism employed is carried directly by the bows of the 50 cover of the automobile and may be readily swung to the position for operation. It should be further understood that when the device is not being used, the same may be readily swung to the position upon the bows 55 of the cover of the vehicle so as to be out of the way and may be firmly clamped upon one of the bows of the cover to hold the same against rattling. It should be further 60 understood that owing to the fact that all of the parts are formed of metal, and that the several parts are adjustable, the parts of the device may be firmly held so as to prevent the bows from becoming accidentally released from the socket 14 adapted to support 65 the same. It should be understood that

the device upon each side of the vehicle is constructed similarly, and it is thought necessary to only describe the specific construction of one of the complete devices.

Having thus described the invention what 70 is claimed as new, is:—

1. An adjustable bow socket comprising a support, said support provided with a laterally extending end, a notch formed near one end of said laterally extending end, a socket 75 member carried by said laterally extending end, said socket member provided with an elongated slot, an adjustable link adapted to be carried by a bow, means for holding said adjustable link at a set angle relative to a 80 bow, adjustable means carried by said link for engaging said notch in said laterally extending end of said support for holding said link in engagement with said support, and means engaging said slot in said socket for 85 holding said link in engagement with said socket.

2. An adjustable bow socket comprising a support, said support provided with a laterally extending end, a notch formed near one end of said laterally extending end, a socket member carried by said laterally extending end, said socket member provided with an elongated slot, an adjustable link adapted to be carried by a bow, means for holding said adjustable link at a set angle relative to a bow, adjustable means carried by said link for engaging said notch in said laterally extending end of said support for holding said link in engagement with said support, and said link provided with an upwardly extending end adapted to fit in said elongated slot in said socket for firmly holding said link in engagement with said socket. 95

3. A device of the class described comprising a support, a socket member carried by said support, a supporting plate adapted to be carried by a bow, said supporting plate provided with a locking rib, a threaded pin 100 extending from said rib, a primary link provided with a longitudinally extending slot fitting over said threaded pin, notches formed upon said primary link for engaging said rib, means for locking said supporting plate and adapted to engage said rib upon said plate, means for clamping said plate in engagement with said rib, means formed upon said plate for engaging said socket member, and an adjustable link carried by said plate for engaging said support. 105

4. In a device of the class described the combination with a plurality of bows, a support, a socket member carried by said support, said socket member adapted to support a bow, each bow provided with spacing means, a primary link carried by one of said bows, a locking plate carried by one of said bows and engaging said primary link for holding the same at a set angle relative to said bow, said socket member provided with 110 115 120 125 130

an elongated notch, said primary link provided with an upturned end for fitting in said notch for clamping said bows in a set position, and an adjustable link carried by
5 said primary link and engaging said support for holding said primary link in engagement with said support.

In testimony whereof I hereunto affix my signature in presence of two witnesses.

GEORGE E. ROBINSON.
